UNITED STATES PATENT OFFICE.

THOMAS WILLIAM WORSDELL, OF WANSTEAD, COUNTY OF ESSEX, ENGLAND.

COMPOUND STEAM-ENGINE.

SPECIFICATION forming part of Letters Patent No. 360,834, dated April 5, 1887.

Application filed March 18, 1885. Serial No. 159,308. (No model.) Patented in England January 23, 1885, No. 999, and in France March 30, 1885, No. 167,961.

To all whom it may concern:

Be it known that I, THOMAS WILLIAM WORSDELL, a subject of the Queen of Great Britain and Ireland, residing at Wanstead, in the county of Essex, Kingdom of Great Britain and Ireland, have invented new and useful Improvements in Compound Steam-Engines, (which have been patented to me as follows: Great Britain, January 23, 1885, No. 999, and France, March 30, 1885, No. 167,961,) of which the following is a specification.

This invention has reference to compound steam-engines of the locomotive type, but may be applied in engines for other uses. A description of it as applied to an inside-cylinder locomotive-engine will enable the nature of the invention to be clearly understood. Two cylinders are employed—one for high pressure and the other for low pressure—so arranged that they can be applied to the same cranks, rods, valve-gears, reversing-motion, &c., as in an ordinary high-pressure engine, the pistons operating on one crank-axle in the usual way.

One of the cylinders (the high-pressure or smaller one) takes steam direct from the boiler. When this steam is exhausted, it passes through a superheater pipe or chamber to the low-pressure cylinder. After performing its function therein, the steam from the low-pressure or larger cylinder is exhausted direct up the chimney, or, where required, can be passed through a feed-water heater, or wholly or partially condensed by being led into the water-tank of the engine or tender.

To render the engine efficient in starting, if the crank on the high-pressure side should be on a dead-center, an auxiliary or starting valve is provided, by which steam can be conveyed direct from the boiler to the low-pressure or larger cylinder, and in order to prevent such steam filling the exhaust-steam pipe or chamber of the high-pressure cylinder, and consequently, also, the high-pressure or smaller cylinder itself through the exhaust-ports, there is provided a valve that I will call the "intercepting-valve." It is applied in the exhaust pipe or passage that connects the two cylinders, and is arranged between the starting-valve and the high-pressure-exhaust orifice. (Conveniently, it may be just above the starting-valve.) When closed, this intercepting-valve will pre-

vent the steam getting back to the high-pressure piston. This valve may be of any suitable kind—such, for example, as disk, butterfly, or slide; but I consider it advantageous to use a flap or foot valve closed by hand-gear from the foot-plate, and thrown back so as to leave a clear passage immediately the exhaust takes place from the high-pressure cylinder. A flap-valve, as described, is preferred, as it can be closed at will, and will always be thrown open by the steam itself when exhausting commences from the high-pressure cylinder, thus leaving the passage unobstructed. The starting-valve may be arranged to be opened by hand against a spring, so as when liberated to be closed in an automatic manner.

The low-pressure cylinder is or may be fitted with a relief-valve at each end, to prevent the cylinder being charged at too high a pressure when steam is admitted direct from the boiler through the starting-valve. Such valves will also become self-acting waste-cocks for the expulsion of water. My invention, as described, may be carried out under various arrangements, and is applicable to ordinary locomotive-engines, whether of the inside or outside cylinder type. As will be evident, an intercepting-valve, such as above described, is applicable to engines of various types wherein exhaust-steam passes from a high-pressure cylinder to do duty in a low-pressure cylinder and where a starting-valve is applied.

In the accompanying drawings, Figure 1 is a vertical section through the smoke-box of a locomotive-engine according to this invention; and Fig. 2, a detail view, in section, of the superheater-pipe.

The high-pressure cylinder *a* receives its steam from the boiler in the usual manner, the distribution of the motive fluid being effected by any suitable arrangement of valve and valve-gear. After the steam has performed its office in the cylinder, it is exhausted into the pipe *b*, which traverses the smoke-box and acts as a superheater. This pipe delivers the steam to the valve-chest of the low-pressure cylinder *c*, from which it passes into the cylinder, and from thence into the exhaust or blast pipe *d*.

In the pipe *b*, which forms the communication between the two cylinders, there is a

branch, *e*, connected to the boiler, and serving for the admission of full-pressure steam to the large cylinder *c* when required. This branch *e* is commanded by an auxiliary starting-valve, 5 *f*, which can be opened and closed from the foot-plate. Fig. 3 is a vertical section of this auxiliary starting-valve with a portion of the branch *e* attached thereto. Fig. 4 is an elevation at right angles to Fig. 3; and Fig. 5 is a section on the line *x x*, Fig. 3, with the valve proper, *f*, removed. There is also arranged in the pipe *b*, between the inlet of the branch *e* and the high-pressure cylinder, an intercepting-valve, *g*, which is shown in section in the 10 detail view, Fig. 2. This is shown in the drawings as a flap or foot valve mounted upon a spindle and operated by a lever which can be manipulated from the foot-plate, either simultaneously with the auxiliary starting-valve 15 or independently of it. When the intercepting-valve is open, it allows a clear passage for the steam, the tendency of the pressure during the normal working being to hold the valve open. When it is closed, it prevents the high-pressure steam, which is admitted to the large cylinder through the auxiliary valve, finding 20 its way to the reverse side of the piston in the high-pressure cylinder, as already fully explained. A relief-valve, *h*, is fitted to each 25 end of the large cylinder, to prevent the steam-pressure exceeding a determined amount and to allow escape for any water that may be present therein.

Both cylinders work onto one crank-shaft 30 and have their valves operated in the usual way.

Although the drawings only show the invention applied to a locomotive, it is evident that with simple modifications it is equally applicable to other forms of compound steam- 40 engines.

What I claim in a compound steam-engine is—

A steam-generator, a high and a low pressure cylinder, a steam-inlet pipe leading from 45 said steam-generator to the high-pressure cylinder, a connecting-pipe leading from the exhaust of the high-pressure cylinder to the steam-chest of the low-pressure cylinder, a branch pipe leading from the steam-generator 50 into the said connecting-pipe, and an auxiliary starting-valve, in combination with an automatic intercepting-valve located in said connecting-pipe between the point where said branch pipe enters the same and the high-pressure cylinder, said intercepting-valve being of such a character that immediately exhausting takes place from the high-pressure cylinder the intercepting-valve is automatically 55 opened and always remains open while steam 60 is passing from the high to the low pressure cylinder, but can be closed before the auxiliary valve is opened, substantially as set forth.
